(57) **CLAIM**

The ornamental design for a prismatic refractor with circumferential prisms, as shown and described.

DESCRIPTION

The present application is related to co-pending U.S. patent application Ser. No. 10/349,299 ("Industrial Luminaire with Prismatic Refractor"), filed on Jan. 22, 2003, and co-pending U.S. Design patent application Ser. No. 29/174,635 ("Prismatic Refractor with Circumferential Prisms and Lens"), filed on Jan. 22, 2003, which are both incorporated by reference here in their entirety.

FIG. 1 is a side view of an embodiment of the present invention;

FIG. 2 is an isometric view of the embodiment shown in FIG. 1;

FIG. 3 is a top view of the embodiment shown in FIG. 1; and,

FIG. 4 is a bottom view of the embodiment shown in FIG. 1.
